UNITED STATES PATENT OFFICE.

ELI CLAYBORNE, OF HOT SPRINGS, ARKANSAS.

SNOWPLOW.

1,422,417.

Specification of Letters Patent. Patented July 11, 1922.

Application filed December 4, 1920. Serial No. 428,232.

To all whom it may concern:

Be it known that I, ELI CLAYBORNE, a citizen of the United States, residing at Hot Springs, in the county of Garland and State 5 of Arkansas, have invented certain new and useful Improvements in Snowplows, of which the following is a specification.

This invention has for its object the provision of a substantial and efficient means 10 whereby railroad tracks may be thoroughly cleared after heavy snowfalls and the operation of the railroad permitted to continue without interruption. The invention seeks to provide a snow plow of sufficient 15 strength to penetrate deep snow falls and turn aside the body of the snow as the plow is driven into the drifts or banks of snow by a locomotive coupled to the rear of the plow. The invention also seeks to provide 20 a plow which will be heated so as to readily penetrate and soften the snow immediately adjacent the plow and also to provide a plow of such construction that the high heavy banks will be turned partly aside and 25 the snow will be caused to pack somewhat at the sides of the track and by its packing resist the usual tendency of the piled up snow to settle back upon the track. Another object of the invention is to provide means 30 whereby the loose snow immediately adjacent the track will be prevented from falling back onto the same and the tread surface of the track rails will be relieved of all loose particles of snow or any thin deposit 35 of snow which might otherwise accumulate thereon.

In the annexed drawings—

Figure 1 is a side elevation of a snow plow embodying my improvements;

40 Fig. 2 is a vertical longitudinal section thereof;

Fig. 3 is a plan view, partly broken away, of the front end of the plow;

Fig. 4 is a transverse vertical section.

45 In carrying out the present invention, I employ one or more trucks 1 which may be of any preferred form but are preferably of such dimensions that the floor or platform 2 carried thereby will be low or comparatively 50 close to the tracks. The platform 2 constitutes the floor of a car which may economically be the body of a discarded freight car or may, if so preferred, be built especially for the purposes of the snow plow. The

55 body of this car may be constructed of posts 3 of wood and a roof 4 supported on said

posts but, whatever construction may be employed, the sides of the car and the roof will be covered with metal sheathing 5. Moreover, as clearly shown in Figs. 1, 2 and 60 4, the sheathing upon the sides of the car will be extended below the floor 2 so that it will terminate below the axles of the trucks 1, although it will obviously not extend to such point that it will tend to come 65 into contact with the ties or roadbed. By extending the sheathing downwardly, as illustrated, any loose snow which might tend to slide from the piles or banks at the sides of the track and be again deposited 70 upon the track will be turned aside and the track will thus be kept clear after the snow has been removed therefrom. It will be readily understood that my plow is intended more particularly for use in those moun- 75 tainous sections where the snowfall is very heavy and drifts of considerable depth are frequently formed upon the track, sometimes reaching a height above that of the trains for which the road is established and 80 which require the services of a large force of men and extremely heavy plows ordinarily to effect removal. It will, therefore, be understood that the car which is built in accordance with my invention is to be 85 driven over the road and for that purpose is coupled to the front of a locomotive, and in Fig. 1 I have illustrated a coupling 6 designed to facilitate the connection of the rear end of the plow or car with the front 90 end of a locomotive, indicated at 7. It will also be understood that the car will be provided only with such doors or windows as are necessary to permit access to its interior and that such doors or windows as may be 95 provided will be also reinforced with a sheathing of metal. In Fig. 1, I have indicated a sliding door 8 mounted in cleats 9 upon the side of the car and adapted to abut a vertical cleat 10 at its front end in closed position so that the loose snow cannot drift into the interior of the car. A step 11 of any preferred form may be provided upon the side of the car to facilitate the opening of the door and obtain access to the interior of 105 the car.

Extending between the side walls of the car, at the front end thereof, is a partition 12 which closes the front end of the car, except for a door or man hole 13 formed in the 110 partition. Secured to and extending forwardly from the partition are the horizontal

plates 14 which serve to support the plow proper consisting of forwardly converging sides 15 and a roof 16 extending over the sides and supported by the upper edges 5 thereof and by the partition 12. The roof 16 arches transversely, as will be readily understood on reference to Fig. 2 and as shown in Fig. 4, and also inclines downwardly toward its front edge. The side 10 walls 15 of the plow converge forwardly so that they meet in a ridge or entering point 17 and constitute a large wedge which will readily penetrate and turn aside the bank of snow. A floor 18 is attached in any convenient manner to the lower edges of the side walls 15 of the plow to thereby brace the lower portions of said side walls and also to serve other purposes which will presently appear. The side walls 15 are preferably 15 constructed of two walls of metal which may be placed in close contact, as shown in Fig. 3, or may be spaced apart and reinforced as may be preferred and the horizontal partitions 14 are preferably of such 20 dimensions that their forwardly converging edges will be spaced, somewhat from the walls 15, as shown at 19, and are connected with said walls by brackets 20. The brackets 20 will tend to resist collapse of the side 25 walls, while the spaces 19 will provide for a circulation of heat past the edges of the horizontal partitions and thereby aid in maintaining the desired temperature in the side walls of the plow. As shown at 21, the 30 said side walls 15 of the plow are dished so that their upper rear corners project outwardly beyond the planes of the greater portions of the walls and thereby constitute overhanging projections which will turn 35 aside the upper portions of the snow banks and exert a packing action thereon so that the tendency of the snow at the sides of the track to slide back onto the same will be overcome.

40 45 My invention contemplates the application of heat to the snow as the plow comes into contact therewith and to this end I provide a furnace 22 for burning solid fuel which furnace will be located immediately adjacent the transverse partition or front wall 12 of the car and while the furnace may be of any desired construction it must be so modified as to provide a heat outlet 23 extending forwardly into the interior of the 45 snow plow proper. This heat outlet 23 should be located below the lower horizontal partition 14 so that the hot air and all the products of combustion will be delivered into the snow plow at the bottom of the same and will be turned aside by the said horizontal partition so that they will be caused to play upon the side walls 15 and heat the same in an obvious manner. The heated currents cannot escape except by flowing past 60 the side edges of both horizontal partitions

14 and, consequently, they will be caused to flow upon the entire inner surface of the side walls of the plow and will raise the temperature of the same so that when the plow penetrates a snow drift or bank the heat of 70 the plow will soften the snow to render penetration and deflection of the snow easy. The gases and other products of combustion will eventually be permitted to escape through a smoke pipe 24 rising from the 75 roof 16 of the plow and turned backwardly, as clearly shown in Figs. 1 and 2, so that falling snow will not be permitted to enter the smoke stack and choke the same. Coal or other fuel for the furnace 22 may be 80 stored at the rear end of the car and to facilitate the loading of the fuel, a door 25 is provided in the roof 4.

I also provide means whereby the plow may be heated by liquid or gaseous fuel 85 when the same is available or is preferred. To this end, a tank or reservoir 26 of any convenient form is placed within the car and a supply pipe 27 is carried forward from the lower end of the reservoir, as shown in Fig. 90 2, said pipe being provided with a cut-off valve 28 so that the flow of the fuel may be controlled. Within the plow, burner pipes 29 are provided at the lower portions of the side walls of the plow and directly against 95 the same and these burner coils are directly connected with the supply pipe 27. When the liquid fuel is to be used, access may be had to the burners through the door or man-hole 13 so that the burners may be readily 100 lighted and the flame therefrom will obviously play directly upon the sides of the plow so as to heat the same.

In order to facilitate the removal of ashes or soot, an opening 30 is provided in 105 the floor 18 of the plow and this opening is normally covered by a plate or door 31 as will be readily understood.

There will be a constant tendency of loose 110 particles of snow to drift back onto the treads of the track rails and there is also a tendency of a thin layer of ice to form on the tracks which tends to impede the progress of the plow or of a train, inasmuch as the car wheels cannot under such 115 conditions obtain a firm grip upon the rails. To avoid such conditions, I provide scrapers 32 on the under side of the floor 18 of the plow and these scrapers may conveniently be strips of metal doubled upon themselves 120 or formed into corrugations and secured at one end, the rear ends of the strips, 33, being free so that the scrapers may readily conform to the swaying of the plow while it is at work without being disengaged from 125 the tread of the rail.

A thermometer 34 is provided upon the front wall or partition 12 of the car so that the temperature within the car and the plow may be noted before the work of clearing the 130

track is commenced. Obviously, it is desirable to raise the temperature of the plow before it is driven into the snow as it is easier to overcome the slight cooling of the 5 plow caused by its contact with the snow than it is to initially raise the plow to a high temperature after it has been pushed against the snow.

To facilitate the hauling of the plow 10 about the railroad yard or to meet other conditions under which it may be needful to pull the plow instead of pushing it, I provide brackets 35 upon the plow near the front end thereof to receive a coupling.

15 A headlight 36 is provided at any convenient point upon the front end of the car and lamps of any preferred form may be placed wherever desired within the car.

From the foregoing description, taken in 20 connection with the accompanying drawings, it will be seen that I have provided a very substantial and durable plow which may be efficiently employed to clear railway tracks in sections where snowfall is heavy and apt to 25 form large banks or drifts.

Having thus described the invention, what is claimed as new is:

1. The combination of a car, a hollow plow carried by the car and covering the 30 entire front end of the same, a vertical parti-

tion extending across the front end of the car and forming the back wall of the plow, a door in said partition to establish communication between the car and the plow, horizontal partitions secured upon and projecting forwardly from said vertical partition across the plow, the forward edges of said horizontal partitions being supported upon but in spaced relation to the front walls of the plow, a smoke pipe rising from 35 the roof of the plow, and a heater within the car having an outlet extending through the vertical partition and into the plow below the bottom horizontal partition.

2. The combination of a car, a hollow 40 plow carried by the car and covering the entire front end of the same, a vertical partition extending across the front end of the car and forming the back wall of the plow, a plurality of horizontal partitions secured 45 upon and projecting forwardly from said vertical partition and having their forward edges supported by the front walls of the plow in spaced relation to the same, and means within the car for supplying heat 50 to the plow within the compartment of the same below the lowest horizontal partition.

In testimony whereof I affix my signature.

ELI CLAYBORNE. [L.S.]
